UNITED STATES PATENT OFFICE.

FRANK H. DUNBAR, OF CLEVELAND, OHIO.

ASH HOPPER.

Application filed December 8, 1924. Serial No. 754,564.

This invention relates to hoppers, and more particularly to hoppers adapted for receiving and discharging hot ashes or the like.

- 5 An object of the invention is to provide such a hopper which will successfully resist the heat from the hot ashes or direct radiation from the combustion chamber of the furnace.
- 10 Another object of the invention is to provide structural wall elements which can be manufactured in standard units so that they may be arranged to build a hopper to fit the space available and give a maximum storage.

15 A further object of the invention is to provide wall elements which will also prevent leakage of quenching water that may be used to quench the ashes and thus keep the hopper walls clean and dry.

These and other objects will be apparent from the following description and annexed drawings, in which

Figure 1 is an end elevation of a hopper showing one of the side walls in section.

Fig. 2 is an enlarged vertical section of the side wall.

Fig. 3 is a horizontal section taken on line 3—3, Fig. 1, showing the wall construction.

Fig. 4 is a plan view of one of the metallic wall plates standing on edge.

Fig. 5 is an elevation looking at the inside of a plate.

Fig. 6 is an end view of the wall plates.

Fig. 7 is an enlarged horizontal section forming the vertical locking strip for securing the ends of the wall plates together.

Fig. 8 is a perspective view of a locking strip.

Fig. 9 is a vertical section on line 9—9, Fig. 7.

Referring to the accompanying drawings, the hopper is formed by a plurality of side walls 1 and a bottom 2 having one or more discharge openings. The hopper walls are supported by beams 3 and crossbeams 4, as shown in Fig. 1. In order to carry the walls 1 of the hopper, suitable flanged or angle supporting bars 5 are secured at their upper ends to the beams and crossbeams, and their opposing lower ends carry one or more substantially horizontally disposed gate frames 6 which surround and form the discharge openings. Carried by the gate

frame 6 is a gate 7, indicated in outline in Fig. 1, movable to open and close the hopper in any suitable manner.

Carried by the angle supporting bars 5 are wall plates 8 which are preferably formed of cast iron and in unit sections of sufficient length to extend between and overlap the inner flat faces of the angle bars 5 which are preferably uniformly spaced about the hopper. In case the hopper is of such as length as not to be an even multiple of the length of a standard wall unit, or in case the hopper is formed with walls tapering inwardly or outwardly toward the hopper bottom, special wall plates may be used between the supporting bars at the corners of the hopper and those forming the side walls adjacent thereto. A standard wall plate is shown in Figs. 4, 5 and 6 and comprises a substantially rectangular plate having flat outer sides 9 adjacent its ends and inturned flanges 10. The central portion of the plate may be depressed inwardly at 11 in order to strengthen the plate and to form a substantially flat inner wall surface 12, as will be more clearly seen hereinafter.

The walls 13 forming the depressed panel portion of the wall plates, together with the flanges 10, form inwardly opening channel portions 14. Co-operating with these channels are longitudinally extending clamping bars 15 provided with outwardly extending flanges 16. The flanges 16 are received in the channels 14 so that the outer faces 17 of the flanges 16 engage the inside faces of the sides 9 of the wall plates. Preferably the flanges 16 are sufficiently long so that a clearance is provided entirely around the flanges 10 of the wall plates, thus ensuring that the flanges 16 will engage the wall plates. Also the channels 14 are sufficiently wide so that there is no engagement between the side walls of the channel 14 and the sides of the flanges 16, thus permitting the edges of the flanges 16 to tightly engage the faces of the portions 9 of the wall plates when the clamping bars are drawn tightly up to the supporting bars and allowing lateral adjustment of the plates relative the bars.

In order to secure the clamping bars 15 to the angle bars 5 the clamping bars are preferably formed with outwardly extending flanges 21 having inturned edges 22 providing a narrow slot or channel between them extending longitudinally of the clamp-

ing bar. Headed bolts 25 may have their heads inserted beneath the flanges 22, the body of the bolt projecting through the slot and through apertures at suitable intervals 5 in the supporting bar 5. The threaded ends of such bolts are adapted to receive nuts 26 for clamping the bars 15 tightly in position against the supporting bars.

If desired, a sealing or packing strip 14^a 10 may be located between the flanges 16 and the inside faces of the portions 9 to insure that there will be a liquid-tight joint there-between. Such a strip, however, may be omitted and the spaces between the wall 15 plates and the clamping bars may be made liquid-tight, if desired, by filling the spaces between them with any suitable cement, such as a plastic cement, so that the inner faces of the wall plates, the clamping bars 20 and the cement filling are substantially flush. If no packing be used between the clamping bar and the wall plates, the joint will soon become liquid-tight in case material, such as ash, containing liquid be stored in the hopper 25 per, for the clamping bar and wall plates will rust together along the flanges 16 of the clamping bar and seal the joint.

Preferably the upper edges 27 of the wall plates have their outer faces in substantially 30 the same plane as the side edges so that they bear against the angle bars 5. At the lower edges the wall plates are preferably cut away so that they will overlap the upwardly extending flanges 27 of the row of plates 35 below. By this construction it will be seen the upper and lower edges of the wall plates and the side edges of the wall plates are shaped and interfitted to form substantially tight closures so that there will be no leakage 40 of fluid from the contents of the hopper through the outer walls of the hopper.

The bars 15 are also preferably formed with interfitting rabbeted edges at the top and bottom so that an interlocking joint is 45 procured for preventing leakage. The tongue member is shown at 28 in Figs. 8 and 9 and the rabbet is shown at 29. It is to be understood, however, that any suitable connection between the ends of the bars 15 50 may be used to make a tight joint.

On the inner faces of the wall plates, if desired, may be disposed inwardly extending flanges or ribs 33, 34, on which are supported a refractory lining, preferably 55 comprising a series of lock tile such as shown in Fig. 2. In this case the tile are recessed so that an overhanging lip 35 engages behind the upwardly and outwardly inclined flange 33 and opposing wall 36 of the tile forming 60 the recessed portion is disposed underneath the outwardly extending rib 34. With this construction the tile is securely held on the wall plate so that it cannot be removed by a straight upward push but only by an upward and outward swinging movement.

The lower edge of the tile is flared outwardly so that it overlaps the tile disposed below with a downwardly inclined draining joint. The inside surfaces of the tile are substantially flat to form a flat, inner wall and the joints between successive rows of the tile and between the abutting edges of the tile in each row may be cemented, if desired.

It is to be understood, however, that any suitable refractory lining may be used and that the inwardly extending flanges or hooks may be of any suitable shape to receive a lining, or may be omitted entirely in case no lining is desired. When omitted, it will be obvious that the inner faces of the hopper 8 walls will be smooth, so that the material stored in the hopper may readily pass downwardly toward the discharge opening.

As shown in Fig. 3, the corner supporting bars 5^a are preferably flanged bars having inner faces disposed substantially at angles to each other, to which are secured the ends of the corner wall sections by bolts 37 extending through the edges 38 of these sections. The corner may be made tight by filling the joints between the inner surfaces of the tile linings at the corner with a suitable cement, such as a plastic cement.

It will be seen that the standard wall plates with the inturned flanges 10 can be used at the corners, if desired, and a suitable corner clamping bar similar to the clamping bars in the side walls may be used to clamp the plates of the adjacent walls to the corner bar 5^a.

It will be understood that when it is necessary to use wall plates of other than a convenient standard or unit length in one or more of the walls of a hopper, the supporting bars 5 may be spaced apart a distance more or less than the length of the standard wall plate, either at the corners or in a wall intermediate the corners of the hopper, that is, the wall sections may be standard adjacent the corner bars 5^a at both ends of one side of the hopper and wherever convenient in that wall of the hopper the supporting bars may be closer or farther apart than standard length to receive one vertical row of spiral wall plates.

When the hopper is used for storing ashes or other material which may contain corrosive substances, it is preferable to make the wall plates and clamping bars of cast iron, which, as is well known, is more resistant to corrosion than steel. With the tight joints formed between the wall plates and the clamping bars, the hopper walls are substantially liquid-tight and the supporting bars 5, as well as the bolts 25, which are outside of the wall plates, are protected from the corrosive action of any substances in the hopper.

Furthermore, it is to be understood that the particular forms of apparatus shown and

described, and the particular procedure set forth, are presented for purposes of explanation and illustration and that various modifications of said apparatus and procedure 5 can be made without departing from my invention as defined in the appended claims.

What I claim is:

1. The combination of wall plates having recessed side edges, upright supporting bars, clamping bars having projections fitting into the recesses of adjacent wall plates to form liquid tight closures, said clamping bars having imperforate inner surfaces and having on their outer surfaces projections to receive means to secure them adjustably to said supporting bars and having their ends rabbeted so that adjacent clamping bars will cooperate with each other to form substantially liquid-tight joints.
2. The combination of wall plates having recessed side edges, upright supporting bars, clamping bars having projections fitting into the recesses of adjacent wall plates to form liquid-tight closures, said clamping bars having imperforate inner surfaces and having on their outer surfaces projections extending for a major portion of the length of the bars to receive means to secure them adjustably to said supporting bars, and having their ends rabbeted so that adjacent clamping bars will cooperate with each other to form substantially liquid-tight joints.
3. A sectional metal wall for a hopper comprising spaced steel uprights, a plurality of imperforate, rectangular, cast iron wall plates supported against the inner side of the said uprights, a plurality of substantially rectangular cast iron yokes supported by the uprights and securing the said wall plates thereagainst, each yoke having a lug disposed on the exterior thereof, and detachable means connecting the lug to an upright, said detachable means being adjustable longitudinally of said yoke to different securing positions.
4. A sectional metal wall including in combination spaced uprights, wall plates having end edge portions engaging the inner side of two adjacent uprights, each wall plate overlapping the next lower plate and being overlapped by the next higher plate, and yokes each secured to an upright and overlapping the said end edge portions of the wall plates to position the same against the upright, each of said yokes having a bolt head receiving channel formed on the outer side thereof and extending substantially the entire length thereof.
5. A sectional metal wall including in combination spaced uprights, wall plates having end edge portions engaging the inner side of two adjacent uprights, the outer face of said edge portions having a substantially flat seating face, each wall plate overlapping the next lower plate and being overlapped

by the next higher plate, and yokes each secured to an upright and overlapping the said end edge portions of the wall plates and having seating portions engaging the flat seating faces of said wall plates to position the wall plates against the upright, said seating portions of the yokes being of materially less lateral width than the flat seating faces of the wall plates to permit adjustment of the wall plates relative to said yokes during assembly of the wall structure.

6. A sectional metal wall including in combination spaced uprights, wall plates having end edge portions engaging the inner side of two adjacent uprights, the outer face of said edge portions having a substantially flat seating face, each wall plate overlapping the next lower plate and being overlapped and by the next higher plate, and yokes each secured to an upright and overlapping the said end edge portions of the wall plates and having seating portions engaging the flat seating faces of said wall plates to position the wall plates against the upright, said seating portions of the yokes being of materially less lateral width than the flat seating faces of the wall plates to permit adjustment of the wall plates relative to said yokes during assembly of the wall structure, said yokes each having a bolt head receiving channel formed on the outer side thereof adapted to adjustably receive suitable clamping bolts.

7. The combination of wall plates having recessed side edges, the bottom of the recesses being flat to provide a flat seating face, upright supporting bars, clamping bars having a pair of spaced flanges, each flange being adapted to seat in one of the flat bottomed recesses of the adjacent wall plates to form liquid-tight closures therewith, each of said flanges being of materially less lateral width than the lateral width of the cooperating recess, the space between the side wall of the recess and the flange being adapted to receive a sealing cement, said clamping bars having imperforate inner faces and having on their outer face projections adapted to receive means to secure them adjustably to said supporting bars.

8. A sectional metal wall including in combination a metal upright, two adjacent wall plates having end edge portions engaging the said upright, each of said edge portions being provided with an upstanding flange on the inner face thereof and a substantially flat seating surface extending from the base of said flange, the said edge portions being spaced apart from each other on the upright, and a yoke having portions engaging the seating surfaces of the plate members, said yoke being secured to the upright between the said edge portions of the wall plates and formed to secure the latter in assembled position with respect to the up-

right, the portion of said yoke engaging said seating surfaces being of materially less width than said seating surfaces in order that a material zone of adjustment during assembly may be provided between the wall plates and the yoke.

9. A sectional metal wall for a hopper comprising a plurality of spaced metal uprights, a plurality of substantially rectangular imperforate cast iron wall plates disposed within and supported by the said uprights, each wall plate having a liner supporting flange cast integrally with and extending at an acute angle to the inner side thereof, and, a plurality of imperforate, yoke-like wall units engaging the inner surfaces of the said wall plates to press the same against the said uprights, the said units being secured to the uprights, the yoke engaging portion of the face of the wall unit being substantially flat and materially wider than the wall plate engaging portion of the yoke-like unit to thereby permit lateral adjustment of said wall plates relative to said

yoke-like units during assembly of the wall structure. 25

10. A sectional substantially liquid-tight, metal wall including in combination spaced metal uprights, imperforate metal wall plates disposed within and supported by the uprights, the said plates having peripherally overlapping upper and lower edges, and imperforate wall units overlapping the side edges of adjacent wall plates and having means disposed on the exterior thereof 30 for securing the units to the uprights, said means including a lug on each wall unit and a bolt engaging therewith and secured to an upright, the side edges of the adjacent wall plates having flat seating faces of materially 35 greater width than the cooperating seating faces of said imperforate wall units adapted to permit adjustment of said wall plates relative to said imperforate wall units during the assembly of the structure. 40 45

In testimony whereof, I hereunto affix my signature.

FRANK H. DUNBAR.
